UNITED STATES PATENT OFFICE.

ULRICH WILCK, OF ESSEN-BELLINGHAUSEN, GERMANY, ASSIGNOR TO FRIED. KRUPP AKTIENGESELLSCHAFT, OF ESSEN-ON-THE-RUHR, GERMANY.

MECHANICAL TIME-FUSE.

1,362,519.

Specification of Letters Patent. Patented Dec. 14, 1920.

Application filed September 7, 1920. Serial No. 408,744.

To all whom it may concern:

Be it known that I, ULRICH WILCK, residing at Essen-Rellinghausen, Germany, a citizen of the German Republic, have invented a certain new and useful Improvement in Mechanical Time-Fuses, of which the following is a specification.

My invention refers to mechanical time fuses containing a clockwork disposed within an annular, adjustable casing. The particular characteristic feature of the fuse consists in an arm coupled with an arbor of the clockwork such that the arm is permitted to axially shift on the arbor. The further characteristic feature of this arm construction consists in means by which after the projectile is fired, the arm is thrown by means of a spring against an annular retaining member provided on said adjustable casing. It is the particular purpose of this invention to insure the operation of this arm so that the fuse will set off the charge at the time desired.

In the accompanying drawings, an example of the invention is illustrated. In these drawings:

Figure 1 shows an axial, longitudinal section through the fuse and

Fig. 2 shows a section on the line 2—2 in Fig. 1 seen from the top.

Referring to the drawings, A represents the main fuse body to which is suitably attached, by means of screws running in an annular groove of the body A, the annular adjustable casing B which surrounds the clockwork. C is the main arbor of the clockwork which is hollow and which is operated by the clock spring D. An arm E is coupled with arbor C so that it may shift thereon in axial direction, this arm extending in opposite radial directions. The portion e^1 of the arm located at the right of arbor C (see Fig. 2) is broader and shorter than the opposite end e^2 of the arm. The arm is spring-controlled by means of a spring F located in the hollow arbor which spring tends to throw the arm toward the point of the projectile. Normally, this arm is prevented from moving axially on arbor C in well known manner by means of a lever G which is thrown out of engagement with the arm when the projectile is fired and which when locking the arm, at the same time prevents rotation of arbor C by clock spring D. The adjustable casing B

is provided at its upper portion with an inwardly extending annular rim B^1 which carries an annular retaining member b^2 extending in a plane in parallel to the plane in which the arm rotates, and which is disposed closely adjacent thereto. The member b^2 is of sufficient width in radial direction that both ends e^1 and e^2 of arm E bear against it when the arm is shifted upwardly under the influence of spring F. The central portion of member b^2 is cut out such that it will permit the arm, when in proper alignment with this cut out portion, to pass through the retaining member. As will be seen in Fig. 2, portion b^3 permits arm portion e^1 to pass, and cut out portion b^4 permits arm portion e^2 to pass. At the outer end of the cut out portion b^4 also the cylindrical portion B^1 is cut away as shown at b^5 . The general construction of the clockwork and fuse mechanism is similar to those known in the art and its operation is such that when arm E is rotated into such position that it properly registers with the cut out portion b^4 , it will be thrown upwardly under the influence of spring F, which sets the fuse mechanism into action.

When the projectile is fired, lever G is disengaged in well known manner from arm E so that arbor C is permitted to rotate under the influence of its clock spring D whereby at the same time arm E is thrown against the retaining member b^2 and commences to rotate with the arbor. This slight axial movement of arm E against retaining member b^2 is at first not sufficient to set off the percussion cap. However, owing to the shape of the retaining member b^2 described above, both ends e^1 and e^2 of arm E bear against the retaining member so that the arm is subject to uniform pressure at both of its ends which prevents jamming of the arbor and insures the smooth running of the clockwork and thus certain operation of the time fuse. Arm E moves axially farther only when the clockwork has rotated arbor C sufficiently to bring the arm into register with the correspondingly shaped cut out portions b^3 , b^4 of retaining member b^2 .

As soon as the arm E, which is rotated by the clockwork in the direction of the arrow Y (see Fig. 2) has arrived under the cut out portion b^3 , b^4 , it enters this cut out portion under the pressure of spring F. At the

same time the annular projection g^2 on the arm E slides off of the projection i^2 on the lever J so that this latter swings outward under the action of centrifugal force. This movement causes rotation of the spindle J^2 . At the same time shoulder i^2 slides off the collar k^2 of the firing bolt K and the firing bolt penetrates the primer under the action of the spring k^2 . The time at which the perforation of the primer takes place is, as will be seen from what has been stated above, dependent upon the adjustment which has been imparted to the adjustable casing B and consequently the annular retaining member b^2 . To prevent the adjustment imparted to the adjustable casing from being lost when the shot is fired an arrangement is provided in the well-known way, by which the member B is immovably secured to the body A of the fuse by action of the discharge, when the gun is fired.

Adjustment between the casing B and base A is provided for by screws passing through the casing B. These screws carry projections which engage an annular recess in the base A.

I claim—

1. Mechanical time fuse of the character described having a clockwork for controlling the operation of the fuse mechanism, an adjustable casing surrounding said clockwork, an arm coupled at its center with an arbor of said clockwork and having free-

dom of movement on said arbor in axial direction thereof, a spring suitably disposed and tending to axially move said arm on said arbor in a given direction, a retaining member on said casing adapted to contact with both ends of said arm and tending to normally prevent such axial movement of said arm, said retaining member having a central cut away portion to permit axial movement of the arm when the latter is rotated to register with said cut away portion.

2. Mechanical time fuse of the character described having a clockwork for controlling the operation of the fuse mechanism, an adjustable casing surrounding said clockwork, an arm mounted upon an arbor of said clockwork, said arm being capable of axial movement in one direction, means normally tending to axially move the arm on said arbor, a retaining member on said casing adapted to contact with said arm at both ends thereof to normally prevent axial movement of the arm, said retaining member having a cut away part permitting the axial movement of the arm when the latter is rotated to register with the cut away portion.

The foregoing specification signed at Essen, Germany, this 18th day of May, 1920.

ULRICH WILCK.

In presence of—

HANS GOTTMANN,
JOSEF OLBERTZ.
